The back of the cabinet or the like is conventionally plain.

The dominant features of my design reside in those portions shown in full lines on the drawing.

I claim:

The ornamental design for a cabinet or the like, as shown and described.
